UNITED STATES PATENT OFFICE.

WILHELM VON OECHELHAEUSER, OF DESSAU, AND CARL STEINBECKER, OF LANGFUHR,
NEAR DANZIG, GERMANY.

PUMP.

No. 884,291.

Specification of Letters Patent.

Patented April 7, 1908.

Application filed January 31, 1907. Serial No. 355,132.

to all whom it may concern:

Be it known that we, WILHELM VON OECHELHAEUSER, a subject of the King of Prussia, residing at 29-30, Kavalierstrasse, 5 Dessau, Anhalt, Germany, and CARL STEINBECKER, a subject of the King of Prussia, residing at 6th Jäschkentalerweg, Langfuhr, near Danzig, Germany, have invented certain new and useful Improvements in 10 Pumps, of which the following is a full, clear, and exact description.

Our invention relates to improvements in pumps and particularly that style having a differential piston adapted to be operated by 15 the explosive engine to which it supplies the air and gas immediately to the respective receiving chambers.

It is the object of our invention to construct a simple and efficient pump of the 20 above character and to provide the same with improved cylinders and pistons, and air and gas channels within the frame, as will be more particularly hereinafter described.

In the accompanying drawings,—Figure 1. 25 represents a vertical section of our improved pump, showing its relation to a vertical gas engine with which it may be used; Fig. 2 is a vertical section of the pump casing at right angles to Fig. 1; and Figs. 3, 4, and 5 are 30 horizontal sections taken on the lines 3—3, 4—4 and 5—5 of Fig. 2.

Referring to these drawings, E represents 35 a gas engine of the vertical type with oppositely moving pistons, but which may obviously be of any similar style requiring separate gas and air receiving chambers. The base B of the engine is provided with an extension B', which forms a suitable foundation for the support of the pump. The ex- 40 tension of the base frame may be utilized for the air and gas supply channels within the frame with the air and gas mains, and may be provided with a suitable valve V, as indicated.

45 The pump comprises a suitable supporting frame having two legs N, N' supporting the differential cylinder C. The upper part of the pump cylinder is for the discharge of air and contains a suitable suction chamber 50 10 with mechanically controlled inlet valve 11 and automatically controlled discharge valves 12, having an exit 13 for immediate connections with the air receiving chamber f' in the gas engine. The pump cylinder 55 contains the differential piston consisting of

the piston proper P and a tubular piston rod P'. The relation of the diameters of the piston proper and the tubular piston depends upon the required or desired proportion of gas and air in the explosive mixture 60 and the air required for displacing the gases of combustion after each explosion of the engine. The tubular piston P' is guided in a suitable cylindrical extension 14 at the bottom of the pump cylinder proper. 65 Around the extension is arranged the gas discharging chamber 16, and the suction chamber 17, the latter having the mechanically controlled suction valve 18 and the former having the automatically controlled 70 discharge valves 19 with like exit means 20 for immediate connection with the gas receiving chamber f' in the engine. The upper part of the cylinder is further provided with suitable hand holes 21 for convenient 75 access to the air discharge valves and other hand holds 21^a are provided around the gas discharge chamber 16 for convenient access to the gas discharge valves. The gas suction chamber 17 is connected through the hollow 80 supporting legs n to the hollow space in the base of the frame B', thereby providing a suitable supply channel for the gas to the suction chamber. The mechanically controlled inlet valves 11 and 18 may be double 85 seated valves or piston valves as occasion may require instead of the plain disk valves shown. At the opposite side in the other supporting leg n' is a similar conduit for the air supply. The air is conveyed by means of 90 the additional connecting piece 22 to the air suction chamber 10 at the top of the cylinder C.

The generally employed method of operating the controlling valves of gas engines by 95 means of eccentrics on a driving shaft and connecting gear is avoided in this construction, as the inlet valves for the gas and air are operated by a double lever mechanism in direct connection with the cross head of the 100 piston. Although the quantities of gas and air required are partially proportioned by the differential cylinder capacity, the exact proportion of the gas and air in the explosive mixture required for each stroke under varying loads is controlled by this lever mechanism and a suitably adjustable governor. This lever mechanism consists of a pivoted bar 30 having one end connected by a link 31 to the cross head and the other end to an 105 110

elbow lever 32 on the pump frame. Attached to the other end of the lever 32 are other connecting links 33 and 34 for operating the respective inlet valves 11 and 18 for air and gas. A governor 35 controls the time of opening and closing these inlet valves. This governor may be of any well known design and be driven from the main shaft by means of a belt or gear as circumstances may 5 require. The governor is directly connected by suitable link connections 37 with the rod 35' which, as the governor rises and falls, actuates the trips 38 sooner or later, thereby controlling the time of opening and closing 10 the gas and air inlet valves.

The operation is as follows: On the down stroke of the piston, air is taken into the pump cylinder above the piston through the air inlet valve 11 from the air channels n' 20 and 22 which communicate with the atmosphere; the governor, acting upon the valve 11, regulates the quantity of air required or desired. On the up stroke of the piston, this air is forced through the automatic discharge valves 12 into the air receiving chamber f' of the gas engine, whence, at the proper moment, part of the air will be utilized to displace the gases of combustion of the previous explosion and part to form the explosive mixture for the next explosion; at the same time gas is taken into the pump cylinder below the piston through the gas inlet valve 18 from suction chamber 17 and supply channels, n etc. the governor, also, by 25 acting upon the valve 17, regulates the required or desired quantity. On the subsequent down stroke, this gas is forced through the automatic discharge valves 19, into the gas receiving chamber f^2 of the gas engine, 30 and from there at the proper moment into the working cylinder.

What we claim is:—

1. A pump of the character described having a cylinder, a differential piston therein, 45 an extension from said cylinder, means forming a gas suction chamber around said extension, a valve communicating between said chamber and the cylinder, and means

forming a gas discharge chamber in direct communication with a gas engine. 50

2. A pump of the character described having a supporting frame, a cylinder, a differential piston therein, means forming an air-receiving chamber in the upper part of said cylinder, a valve therein, and means forming a discharge chamber adapted to directly communicate with a gas engine. 55

3. A pump of the character described having a supporting frame of two legs, a cylinder with a differential piston therein, means forming air and gas suction chambers in said cylinder, one of said legs having a conduit therein communicating with the air suction chamber, and the other leg having a conduit communicating with the gas suction chamber. 60

4. A pump for supplying air and gas to a gas engine, a cylinder having a differential piston therein, means forming suction chambers for air and gas respectively, valves for 70 opening and closing said chambers, and means connected with the cross head of said piston for operating said valves, and a governor connected therewith whereby the opening and closing of the said valves may be 75 regulated.

5. A pump for supplying air and gas to a gas engine, comprising a supporting frame, a cylinder, a differential piston therein, and means forming a gas discharge chamber on 80 the lower part of said cylinder adapted to communicate directly with the gas engine.

In testimony whereof we have signed our names to this specification in the presence of two subscribing witnesses.
